UNIVERSAL DEMODULATOR FOR FREQUENCY AND AMPLITUDE MODULATION

Edward H. Lange, Baltimore, Md.

Application February 2, 1943, Serial No. 474,468

12 Claims. (Cl. 250—27)

This invention pertains to thermionic demodulator devices for converting the pattern of frequency-modulation of a high-frequency carrier-voltage into corresponding output-voltages, and more particularly to apparatus for compensating undesirable modifications introduced or superposed upon these output-voltages by extraneous amplitude-modulation of the carrier-voltage, either at random, or by desired amplitude-modulated signal intelligence; and for utilizing the identical component parts and operating structure of the demodulator device, for also demodulating amplitude-modulation, to accomplish economy of necessary component parts, and of space to accommodate these parts.

The principal object of this invention, is to provide such a universal demodulator, having both high sensitivity of conversion, and economy of component parts.

Another object of this invention, is to provide such a demodulator capable of converting frequency deviations above and below a centre frequency into respective positive and negative voltages, directly proportional to the magnitude of the frequency deviations, without the necessity of regulating the impressed voltage upon the demodulator to a minimum determined by the weakest impressed signal, to eliminate amplitude-modulation; to provide operation of the frequency-demodulator from a variable norm of impressed voltage upon the demodulator, by providing apparatus for compensating the effect upon the sensitivity of the frequency-demodulator, of variations of magnitude of the impressed frequency-modulated voltage, and by providing a selection of operating-magnitudes of impressed voltage.

Another object of this invention, is to provide in a frequency-demodulator, a useful unidirectional control-voltage, which varies in direct proportion to amplitudes of the alternating currents supplied to the input-side of the demodulator, and which is independent of the frequency deviations from centre-frequency of these alternating currents, over the entire useful range of such frequency deviations.

A further object of this invention, is to provide a balanced frequency-demodulator, and capable of operation with a push-pull amplifier connected to the output-side of the demodulator, and to provide selector means for utilizing the same amplifier and the same demodulator for the reception of intelligence impressed upon the demodulator in the form of amplitude-modulation.

Still another object of this invention, is to provide a universal demodulator, requiring no thermionic tube or tubes for amplitude-limitation ahead of the frequency-demodulator, and to provide a useful bridge-connection between the output-sides of the demodulator, for separating the component demodulations, resulting from frequency-modulation and from amplitude-modulation.

These objects, and others, are hereafter set forth in further detail in the following specification and appended claims, and will be better understood by reference to the drawing.

In the drawing,

Fig. 1 illustrates a universal demodulator in accordance with the principles of this invention, having a thermionic compensator-tube, a double-diode, a resonant circuit and choke-coil connected to the double-diode, output resistors for reception of either demodulated amplitude-modulation or demodulated frequency-modulation; the resonant circuit and connected choke coil being capacitively coupled with impressed modulated alternating currents, and the cathode-anode conductance of the compensator-tube being capacitively coupled with the resonant circuit.

Fig. 2 illustrates a universal demodulator in accordance with the principles of this invention, having a thermionic compensator-tube, a double-diode, a resonant circuit and choke coil connected to the double-diode, output resistors for reception of either demodulated amplitude-modulation or demodulated frequency-modulation; the resonant circuit being inductively coupled with the impressed modulated alternating currents, the connected choke coil being capacitively coupled with the impressed modulated alternating currents, and the cathode-anode conductance of the compensator-tube being inductively coupled with the resonant circuit.

Fig. 3 illustrates in diagram form, variations of cathode-anode conductance of the compensator-tube in relation to bias-voltage upon the control-grid of this tube, and variations of total conductance with the bias-voltage, employed in this invention to modify voltages developed in the resonant circuit by the impressed alternating currents.

Fig. 4 illustrates in vector-diagram form certain unique relationships found to exist with reference to voltage and current magnitudes in the structures of Fig. 1 and Fig. 2, and employed to yield the unidirectional control-voltage of this invention, directly proportional to the amplitudes of impressed alternating current, and independ-

ent of frequency deviations from the centre frequency.

Fig. 5 illustrates a push-pull resistance-coupled thermionic amplifier, for amplifying the selected output of the demodulators, and illustrates selector means for operation from demodulated signals of either frequency-modulation or amplitude-modulation.

Referring to Fig. 1, the principal input-terminals are shown at 51 and 52, the terminal 52 being connected to the negative terminal of a source 29 of unidirectional voltage, the positive terminal of the source 29 being connected through the choke-coil 28 to the terminal 51. Between the terminals 37 and 38 is a resonant circuit, and at 5 is a choke coil, the resonant circuit 37-38 and choke 5 being connected in series, and capacitively coupled across the terminals 51-52, by the condenser 52b.

At 30 is illustrated a thermionic tube having an anode 42, a cathode 34, a suppressor-grid 31 directly connected by connection 33 to the cathode terminal 34a; a screen-grid 32 connected to the source 29 by connector 32a, a control-grid 35a connected to terminal 35, and direct connection 25 of cathode terminal 34a to terminal 52, and to auxiliary input-terminal 36. Terminals 35 and 36 provide means for impressing amplified modulated alternating voltages across the terminals 51 and 52. The present invention is not directly concerned with the structures preceding the demodulators of this invention, in the sequence of apparatus utilized from initial reception of signals to final output of intelligence, and the connections of tube 30 to 51-52 are illustrated only for purposes of continuity, there being many well-understood types of linkage with such preceding structures, capable of supplying the required modulated alternating voltages to the principal terminals 51-52.

At 11 is a variable condenser for tuning the resonant circuit between 37 and 38. Between 37 and terminal 10b of the condenser 11, is an inductance coil 39, having the parts 8, 9, and 12. For the purpose of this invention, it will be understood that the coil 39 may be a single continuous coil having the connections 10, 38 and 10b thereon, or may be made up of separate coils in series, either without mutual inductance, or with additive mutual inductance between coils, and constituting a single inductance coil between 37 and 10b.

At 13 is a double-diode, having anodes 15 and 16, and cathodes 14 and 11. Connected between the cathodes 14 and 11, are the equal resistances 18 and 19 in series, forming a single resistance, and having the connection 50 at the half-resistance point upon this resistance. At 20 is a condenser shunted across 19 and at 20a is a condenser shunted across 18. The anode 15 is connected to the anode 16, through the conductive path 15a, 10b, 38, 10, 16a, the lead wires 15a and 16a being directly connected to the respective anodes 15 and 16, and to the included parts 12 and 9, of the inductance of the resonant circuit 37-38. The terminal 38 upon inductance coil 39, is located with reference to the terminals 10 and 10b, so that at exact resonance of the resonant circuit 37-38 the alternating voltage across 10-38 is equal to the alternating voltage across 38-10b, the terminal 38 being at the half-inductance point upon the part of inductance coil 39 included in the conductive path between the anodes 15, 16. At 23 is a resistance, connected from half-resistance point 50 to the connector 31', which connects with 75

the ground connection 55, with the terminal 52, and with terminal of choke coil 5, through the voltage-bias resistance 5c connected to 29, or through condenser 5c. Shunted across the resistance 23, is the condenser 26. The equal resistances 22a and 22 are connected in series, and connected across the cathodes 14-17, through the stopping condensers 21 and 21a, and the half-resistance point 22b of the total series resistance, is connected to ground 55, and to the terminal O'. Similarly, the resistance 24 is connected across the resistance 23 through a stopping condenser 25, one terminal of 24 being directly connected to the ground connection 55, the other terminal being connected to the terminal A1. At F1 and F2, are output terminals, F1 being connected directly to the ungrounded terminal of 22, and F2 directly to the ungrounded terminal of 22a. The terminals F1-F2 are for demodulated frequency-modulation, and the terminals O'-A1 for demodulated amplitude-modulation.

At 1 is a thermionic compensator-tube, having anode 2, cathode 3, and control-grid 7. Connected to the common terminal 4d, between choke-coil 5 and terminal 38 of the resonant circuit, is the terminal 3a of cathode 3. The anode 2 is connected to the terminal a, which is connected to terminal b by a removable link, the terminals a, b, being terminals of a switch. The terminal b is connected to terminal 27 of the coupling condenser 52b, which terminal is directly connected to the principal terminal 51. Connected to the resistance 23 is the adjustable connector 7b, which is connected to the control-grid 7 through the choke-coil 5a. The choke-coil 5a is connected in parallel with choke-coil 5, through the condensers 6, 6b, and 6c, the condenser 6c having one terminal connected to the choke-coil 5, and the other terminal connected to terminal 52, through conductor 31'. The terminal of condenser 5c which is connected to the choke-coil 5, is also connected by an adjustable connector to the bias-resistance 5c. The bias-resistance 5c has one terminal connected to terminal 52, at the negative-end of source 29, and the other terminal connected to a positive terminal upon the source 29.

Referring to Fig. 2, the variable condenser 11a is connected across the parts 9a and 12a of the inductance coil 39', to form a resonant circuit. The terminal 38a upon the inductance coil 39' is connected to a terminal of the choke-coil 5b, and the opposite terminal of the choke-coil 5b is connected through the resistance 23 to the half-resistance point 50 upon the resistor formed by 18 and 19, in series.

The principal terminals for application of modulated alternating voltages, in the circuit of Fig. 2, are 51a and 34a. As discussed with reference to Fig. 1, connections of the tube 30 with the principal terminals of this demodulator, are illustrated only for purposes of continuity, and in reference to the utilization of the source 29 of unidirectional voltage, of this invention.

The series connection of resistances 18 and 19, and connection across the cathodes 17 and 14, is identical with Fig. 1, as is likewise the connection of resistances 22 and 22a, and condensers 21 and 21a, and terminals F1, O', and F2. Similarly, the resistance 23 is shunted by the condenser 26, and the resistance 24 is connected across 23, through the stopping condenser 25, the common terminal of choke-coil 5b, resistance 23, and resistance 24, being connected to the ground 55.

Across the principal terminals 34a-51a is the

inductance coil 39a, in series with the by-pass condenser 41, and having the tuning condenser 40 shunted across its terminals. Connected to the junction 51b, between the by-pass condenser 41 and coil 39a, is the positive terminal of the source of unidirectional voltage, 29; the negative terminal of 29 being connected to the ground, 55. The terminal 10c of the resonant circuit 39'-11a, is connected by the conductor 18a directly to the anode 16, of the double-diode 13, and the terminal 10d of this resonant circuit is connected directly to anode 16, by conductor 18a. The choke-coil 5b is energized by the capacitive coupling with the impressed modulated voltages across 51a-34a, through the condenser 52a, and connection 55 to ground. The coil 39a has mutual inductance with coil 39', and the resonant circuit 39'-11a is thus energized by the mutual inductance with the coil 39a, which coil is shunt-connected to the input-terminals 51a-34a. The junction 38a upon the inductance coil 39', is at the half-inductance point upon 39', such that the alternating voltages across parts 9a and 12a are equal.

The cathode 3 of the compensator-tube 1 has its terminal 3a directly connected to the bias-resistance 5c, by a variable connector, the bias-resistance 5c having one terminal grounded at 55, and the other connected to a positive terminal upon source 29. The screen-grid 32 of tube 30 is connected to the source 29 by connector 32a, and the condenser 32b is connected between the screen-grid 32 and cathode terminal 34a. The control-grid 35a is terminated at terminal 35, and terminal 36 is connected to 34a, and to ground 55. The terminals 35 and 36 serve as input terminals for applying amplified modulated alternating voltages across the principal terminals 34a-51a. The suppressor 31 is connected directly to the terminal 34a of cathode 34, it being understood that this connection can be within the tube-enclosure, in a manner commonly used.

Referring to Fig. 5, a resistance-coupled push-pull amplifier is shown, having thermionic tubes 71 and 73; tube 71 having anode 72, cathode 75 and control-grid 77, and tube 73 having anode 70, cathode 74, and control-grid 78. Cathode 75 is connected by biasing resistance 67 to ground, and likewise cathode 74 is connected to ground through biasing resistance 68. By-pass condenser 68 is connected across 67, and by-pass condenser 69 is connected across 68. A source of unidirectional voltage 29a has its negative terminal connected to ground through conductor 79. Resistance 65 connects anode 72 with the positive terminal 76 of 29a, and resistance 65' connects anode 70 with terminal 76. Anode 72 is connected through stopping condenser 64 and resistance 61 to ground, and likewise anode 70 is connected through stopping condenser 63 and resistance 62 to ground. Terminals 57, 59, and 60, are output-terminals of the amplifier. At 80, 81, and 82, are switch-blades, simultaneously movable by the control-knob 86 connected to the non-conducting member 83, which is pinned to each of the switch-blades, in a manner well understood. There are two positions in which the switch is used; in position one, as illustrated, the compensator-anode switch 80, connects a and b together, switch 81 connects grid 77 with terminal F₁', and switch 82 connects grid 78 with terminal F₂'. In position two, as shown by 81' and 82', switch 80 disconnects a from b, switch 81 connects grid 77 to terminal A₁, and switch 82 con-

nects grid 78 to terminal A₂', which terminal is connected by the variable contactor 58 to resistance 61, for phase-inversion. The reasons for utilizing the phase-inverting connection, will be subsequently pointed out.

An important feature of this invention is the bridge-means employed to permit interconnection between the output-circuits for frequency-demodulation and for amplitude-demodulation. It will be noted that the output resistance 23 for amplitude-demodulation is connected from the half-resistance point between the cathodes of the double-diode, to the half-resistance point between the output-terminals for frequency-demodulation, F₁ and F₂. Thus, variation of voltage amplitude across the junction 50-O' produces no resultant voltage between F₁ and F₂, and likewise variation of voltage amplitudes between the cathodes 14-17, across resistances 18, 19, produces no resultant voltage across the terminals A₁-O'. The utilization of the above-mentioned balanced circuit connections in the universal demodulators of this invention, will be better understood upon subsequent consideration of the means of this invention, providing a unidirectional control-voltage in the frequency-demodulator. The frequency-demodulated voltage between the terminals F₁ and F₂ specifically provided to be separate from any superposed effects of amplitude-modulation by the above-disclosed bridge-means, is readily applied to the amplifier of Fig. 5, by any one of many well-understood linkages of conventional usage, for example, by a transformer with primary connected across the terminals F₁ and F₂, and secondary having terminals F₁' and F₂', and a grounded centre-tap O'.

In Fig. 2, grid 7 of the tube 1 is connected by 7b to a variable contact on resistance 23, and high-frequency by-pass condenser 26b connected from 7b to cathode terminal 3a serves to keep voltages of the high-frequency from being impressed upon the grid 7. The anode 2, of compensator-tube 1, is connected to terminal a, which connects to terminal b by a removable link, and terminal b is connected by means of the variable conductor 40a to the inductance coil 39a. When the circuit between a and b is closed, the compensator cathode-anode conductance g_t is thus coupled with the resonant circuit 39'-11a by the mutual inductance between 39a and 39'. It will be evident that the cathode-anode compensator conductance g_t can be alternatively coupled with the resonant circuit 39'-11a by a tertiary coil connected between 51b and 40a, instead of by coil 39a.

Having illustrated certain circuit connections embodying this invention, the principles of this invention are hereafter discussed to point out the important features, and with reference to the above-disclosed circuit connections.

In devices hitherto employed for demodulating frequency-modulated alternating currents, it has been necessary to eliminate any variations in amplitude of the impressed alternating currents, since such devices are also responsive to amplitude variations; without such elimination the resultant response to the frequency modulation would be distorted by extraneous voltages unrelated to the frequency modulation. Devices hitherto employed, and requiring one or more tubes to accomplish satisfactory elimination of amplitude variations, have employed a saturation principle, wherein alternating currents impressed in excess of a certain minimum value are unable to produce at the output side alternating currents larger than the minimum value. Such

devices result in the employment of signals determined by the weakest signal-strength, and but little gain is contributed by the tube or tubes themselves, which are used to so limit the signal amplitudes. It is therefore necessary to provide, by means of the amplifying apparatus preceding such a limiting device, an excess of amplification, such that the weakest signal will upon amplification equal the constant norm fixed by the characteristics of the limiting device, and no benefit is thus derived from the signals which exceed such a fixed minimum. In the devices of this invention, operation of the demodulators takes place upon a selectable norm of input-signal amplitude, modifications of the amplitude of input signals being compensated in their effect upon the frequency-demodulation.

In order to provide operation of the frequency-demodulator from a selectable norm of alternating current magnitudes, and to provide compensation for variations of the alternating current amplitudes above and below the selected norm, that is, compensation for the effect of such variations upon the conversion-sensitivity of the frequency-demodulator, it is necessary to provide a unidirectional control-voltage which is directly proportional to the amplitudes of the alternating currents impressed upon the demodulator, and which is, at the same time, independent of the frequency deviations from centre-frequency, for the entire range of such deviations employed upon the frequency-demodulator. The discovery of means for producing such a control-voltage in a frequency-demodulator, is an important feature of this invention, in addition to the apparatus utilizing this control-voltage to compensate for amplitude variations, and permitting operation upon a variable norm.

The principle of operation of the unidirectional control-voltage, will be first pointed out for Fig. 1, wherein a resonant circuit 37-38 is in series with a substantially pure inductive reactance between the terminals 4d and 52, the choke-coils 5 and 5a being high-inductance chokes, in parallel across these terminals, the impedance of the condensers 6, 6b, and 6c being negligible in relation to the inductive-reactance at the centre-frequency of 5 or 5a. Also the condenser 52b has a negligible impedance in relation to either 37-38 or the choke-coils 5 and 5a in parallel, and serves primarily to keep the total potential of source 29 from the anodes 15, 16, of the double-diode. When the anode 2, of the compensator-tube 1, is disconnected by means of removable connector between a and b, and the resistance 23 is short-circuited, there is present an uncompensated frequency-demodulator, operable upon frequency-modulated constant-amplitude alternating currents in the input circuit, 27-31-38-4d-52, and providing frequency-demodulation across the output terminals O'-F₁ and O'-F₂. The conditions then existing, can be better understood by reference to Fig. 4. At 5e is shown a vector representing the alternating voltage across choke-coil 5; this vector is displaced in phase by 90 degrees from the alternating current through the chokes 5, 5a. The resonant circuit 37-38 is sharply resonant to the centre-frequency, the inductance coil 39 having a very high reactance-resistance ratio. Thus, at exact resonance for the centre-frequency, the alternating voltage across 37-38 is in phase with the alternating current passing through chokes 5 and 5a, and is therefore 90 degrees displaced in phase from 5e. At A is shown the vector voltage across

the part 9 of resonant circuit 37-38, and at B is shown the vector voltage across the part 12 of the resonant circuit, at exact resonance to centre-frequency. When the voltage across 9 is directed toward 38, the voltage across 12 is directed away from 38. The voltage impressed across the anode-cathode 15-14 is determined by the resultant voltage across 10b-37', and likewise the voltage impressed across the anode-cathode 16-17 is determined by the resultant voltage across 10-37'. At exact resonance, these resultant voltages are equal, and are shown by E₁' and E₂'. The corresponding unidirectional currents through the diodes, are proportional to these resultant voltages, and equal unidirectional currents flow from the cathodes through 19 and 18 to the junction 50, there being no resultant unidirectional voltage across 18 and 19 in series, that is, between the cathodes 14 and 17. Condensers 20 and 20a have a negligible impedance for the high or centre-frequency, in relation to the resistance 18 or 19. For a constant alternating current through the resonant circuit, the locus of the voltages across 9 and 12 is given respectively by the circles n and n'. For a small percentage change of the frequency from the centre-frequency, the sharply resonant circuit 37-38 will have the voltage across 9 de-phased by 45 degrees, by this frequency-deviation; the voltage across 9 is then represented by the vector 9e, and likewise the voltage across 12 is then represented by 12e. The resultant alternating voltages across the diodes are now represented by E₁ and E₂, and the currents flowing to the junction 50 are unbalanced, there being a greater unidirectional current through 18 than through 19, toward 50. For a frequency deviation on the opposite side of the centre-frequency, this condition is reversed. There is thus produced across 14-17 a unidirectional voltage, which varies in direct proportion to frequency deviations from centre-frequency, over a useful range of frequency deviations, the unidirectional voltage being zero at the centre-frequency, and of opposite polarities for deviations above and below centre-frequency.

It will be noted that the total unidirectional current, that is the arithmetic sum of both diodes, flows through the conductor 50a, from junction 50. This total current, in general, varies with frequency deviations, and is therefore not inevitably an index of the magnitudes of alternating currents flowing through the input circuit 27-31-38-4d-52; thus, even when the amplitude of input-alternating currents is constant, the total unidirectional current through 50a will in general vary over a wide range with frequency deviations employed for frequency-modulation. An important feature of this invention is the means for obtaining independence of this total unidirectional current of frequency deviations, over the entire useful range of such frequency deviations, in the frequency demodulator, and for obtaining direct proportionality between the total unidirectional current and the amplitudes of impressed alternating current.

Thus, it will be seen from Fig. 4, that while the resultant voltage across 14-17 due to frequency deviations is determined by the arithmetic difference of voltages E₁ and E₂ for any particular frequency deviation, that is, by the difference in unidirectional currents through the equal resistances 18 and 19, the sum of these unidirectional currents is determined by the sum of the voltages E₁ and E₂ for any particular fre-

quency deviation. The variation of this sum, with frequency deviations, can be illustrated from Fig. 4, in reference to the voltage ratio employed, for the ratio of alternating voltage across choke-coil 5 to alternating voltage across the resonant circuit 37-38, at the centre-frequency. Thus the vector A is a measure of the half-voltage across 37-38, when the junction 10 is at half-voltage across 37-38, and comparison can be readily made between the sum $E_1' + E_2'$ for resonant frequency, and $E_1 + E_2$ for frequencies deviated from resonance sufficient to de-phase the voltages across 9, and across 12, by 45 degrees, as influenced by the ratio of 5e to A+B, that is, the ratio of voltage across choke-coil 5 to voltage across resonant circuit 37-38, at centre-frequency. Designating this latter ratio by N, then the percentage variation of $E_1 + E_2$ from $E_1' + E_2'$ as related to N, is approximately as follows: When N is $\frac{1}{3}$, variation is 29.5 per cent; when N is $\frac{1}{2}$, variation is 19.0 per cent; when N is 1, the variation is 7.6 per cent; when N is 2, the variation is 2.2 per cent; and when N is 3, the variation is 1.0 per cent. When the ratio N which is employed, is sufficiently large, the total unidirectional current can thus be made independent of the operating frequency-deviations upon the frequency-demodulator, to the extent required. When frequency-deviations are less than those sufficient to de-phase the resonant circuit voltages by 45 degrees, the percentage variations will be somewhat less, but since frequency-deviations must be a substantial percentage of this magnitude to yield proper operation of the frequency-demodulator, it is apparent that the ratio $N=1.0$, defines a minimum ratio, below which the total unidirectional current would be unsatisfactory for controlling unrelated variations in the amplitudes of impressed alternating currents, or controlling the effect of such amplitude variations upon the input of the frequency-demodulator. The voltages E_1' and E_2' are, however, directly proportional to the magnitude of alternating current through the input circuit 27-37-38-4d-52, being compounded from 5e and A or B, each of which is directly proportional to the impressed alternating current. The employment of a ratio N greater than unity, together with the total unidirectional current from the diodes, thus provides an important control means for annulling the effect of varying alternating current amplitudes upon the output of the frequency-demodulator.

In this invention, the resistance 23 is connected in series with the total unidirectional current from the diodes, to produce a unidirectional control voltage, directly proportional to the amplitudes of the impressed alternating currents, and independent of frequency-deviations over the entire range of such deviations employed upon the frequency-demodulator. Referring to Fig. 3, a graph is shown, illustrating a variation with negative-voltage bias upon the control-grid 7 of the compensator-tube 1, of total conductance, consisting of a circuit conductance and of the cathode-anode conductance of tube 1. The tube-conductance is indicated by g_t , and circuit conductance by g_o . The adjustable negative-voltage bias of tube 1, produced by resistance 5c, is indicated by $-E_7$; at 84 is indicated the various magnitudes of resultant or total conductance across the resonant circuit, e. g. 37-38, indicated by G. The voltage E_7' is the positive voltage introduced upon the control-grid 7 of compensator-tube 1, by the unidirectional control-

voltage from resistance 23, and which varies in direct proportion to the magnitudes of the alternating current amplitudes, impressed upon circuit 27-37-38-4d-52. O is the origin of co-ordinates for the graph of conductance as related to resultant negative bias upon grid 7, and O' indicates the origin thereon, for the unidirectional control-voltage derived from 23.

The voltage-conversion sensitivity of the frequency-demodulators of this invention, that is, the voltage output across 14-17, as related to the magnitude of frequency-deviations from centre-frequency, designated by Δf , to the magnitude of impressed alternating currents, designated by I_{ac} , to the resultant conductance determining the voltage magnitudes of the resonant circuits, designated by G, and to the coefficient K_o , which is fixed by the values of the previously defined ratio N employed, and by the inductance, capacitance, and resistance values of the alternating current networks of the demodulators, is:

$$E_7 = K_o \Delta f \frac{I_{ac}}{G^2}$$

It will be noted that the demodulated voltage-output of the frequency-demodulator, E_7 , varies not only with the frequency deviation Δf , but also with the amplitudes of the alternating currents impressed upon the circuits, and upon the inverse square of the resultant conductance, determining the voltage magnitudes of the resonant circuits.

It is therefore evident, that variations of I_{ac} are of equal importance with variations of Δf , and that to attain satisfactory frequency-demodulation the effect of amplitude-modulation must be annulled. As previously noted herein, this has hitherto been usually accomplished by regulating I_{ac} to constancy, through a saturation-type device, thereby prohibiting usage of any values of I_{ac} other than those identified with the output-characteristic of such a device.

In the demodulators of this invention, the ratio I_{ac}/G^2 is regulated to substantial constancy, thus permitting a very wide range of signal strengths to be utilized directly upon the demodulator. This is an important feature of this invention. Thus, if this ratio is designated by D, then $D=I_{ac}/G^2$ must be a constant value during reception or demodulation of the signals; however, it is evident that a selection of constant values of D exists, over a large range.

When the previously defined ratio N has been brought within the limits disclosed herein, then, the unidirectional control-voltage E_7' produced upon the resistor 23, is directly proportional to the value of I_{ac} of alternating currents in the input-circuit of the demodulator, and independent of the variations Δf . Designating this ratio by S, then $E_7'/I_{ac}=S$ wherein the factor S is selective by the adjustable connector 1b upon the resistor 23. The manner in which the resultant conductance G must be modified to accomplish this result, is therefore:

$$\frac{E_7'}{G^2} = SD$$

and this relationship is indicated by the parabolic curve at 84, Fig. 3. The conductance of the resonant circuit alone, without loading of the cathode-anode conductance g_t of the compensator-tube 1, is shown at g_o ; the variations of g_t with the resultant bias voltage upon grid 7, that is, with $-E_7 + E_7'$, must therefore conform to the difference of ordinates between the parabolic

curve 84 and 86. It will be noted that this difference is substantially a straight line, as indicated by the dotted line 85, and for very large percentage variations of E_7' , about a mean value between O and O''. Such substantially straight-line characteristics of cathode-anode conductance with negative voltage-bias, are attainable in conventional triodes, and also in conventional pentodes, it being understood that for simplicity of illustration tube 1 is shown as a triode, and that a pentode can also be used with a suppressor connected to the cathode thereof, and a screen-grid connected to the source 29. Also, such characteristics are attainable in conventional tubes, with slight curvature toward the origin O, providing even greater conformance with the parabolic curve 84 than indicated by the line 85. It is therefore apparent, that if the mean value of E_7' is selected, a corresponding mean value of I_{ac} is determined by the selection factor S. Thus amplitude-modulation of I_{ac} causes corresponding amplitude-modulation of E_7' , and appropriate modification of G, to maintain the ratio E_7'/G^2 constant, and thus to maintain the ratio I_{ac}/G^2 constant. If it is desired to operate with a larger signal upon the demodulator, for example, a signal ten times the former signal, in mean value, then S is reduced to one tenth its original value by means of variable conductor 1b upon 23, providing the same mean value of E_7' , and thus maintaining a constant value of D ten times as large as the former value.

The impedance of condensers 20, 20a, and 26, is low in relation to the respective resistances shunted by these capacitances, and at the high carrier-frequency, or centre-frequency of the impressed alternating currents; however, these impedances are high in relation to the respective shunted resistances for the low or modulation frequencies. Impedance of condenser 52a is negligible in relation to the impedance of the choke-coil 5b, which is essentially pure inductive-reactance. Condenser 26b has a low impedance at the centre-frequency, and operates as a substantial short-circuit for these frequencies, preventing the carrier frequencies from being impressed upon the grid 7, Fig. 2. Condensers 21 and 21a have low impedance in relation to the resistances 22, 22a, for the low or modulation frequencies of the output-terminals F₁, F₂, and likewise condenser 25 has low impedance in relation to resistance 24, for the low or amplitude-modulation frequencies of the output-terminals A₁, O. In Fig. 1, the circuit traversed for impressing upon grid 7 the variation voltages initiated by changes in amplitude of the impressed alternating currents of the demodulator, is

3a-4d-5-5c-37'-23-7b-5a-7a-7

It will be noted that the equal alternating voltages across 5 and 5a are traversed in opposite directions, and that there is thus no high-frequency carrier voltage impressed upon grid 7, the condenser 6 also serving as a substantial short-circuit between grid 7 and cathode 3 for such voltages.

In the demodulators, when it is desired to receive the intelligence impressed upon the alternating carrier currents, through the medium of frequency-deviations from centre-frequency, the amplifier of Fig. 5 is connected to the terminals F_{1'} and F_{2'} by the switching means shown, which also, then connects the terminals a and b together, and variations of amplitude of the carrier currents either in the form of random modi-

fications or in the form of amplitude-modulation containing signal-intelligence, are compensated for by the compensator-tube 1. When it is desired to receive intelligence impressed upon the carrier currents through the medium of amplitude-modulation, the amplifier is connected to the terminals A₁ and A_{2'}, the latter terminal not being present upon the demodulator, and being connected to the output side of the amplifier in a manner well understood, to impress upon terminal A_{2'} an alternating voltage equal to that impressed upon A₁ by the demodulator, and of opposite phase, thereby utilizing the same push-pull amplifier for amplifying either type of demodulation.

The selector means 86-83-80-81-82, of Fig. 5, is intended for alternate use with the terminals F_{1'}, F_{2'}, and with terminals A₁, O', and when connected to the latter terminals the switch 80 disconnects a from b, and thus removes the compensating action of tube 1. It will be noted that while this is a preferred usage of the demodulators of this invention, both demodulated frequency-modulation and demodulated amplitude-modulation can be simultaneously received, each at the respective terminals F₁, F₂, and A₁, O', with the terminals a and b connected together. For this usage, the employment of larger values of the ratio N previously defined herein, yields an improved correspondence between the amplitude-modulation upon the impressed signal currents and the resultant amplitude-demodulation at A₁-O', and some decrease in the voltage-conversion sensitivity of the frequency-demodulator.

The adjustable negative-voltage bias, $-E_7$, in each instance derived from the resistor 5c connected to the source 29, is employed to set the origin O'', with reference to which the positive-voltage bias E_7' operates to modify the total or resultant conductance G. Thus if the positive-voltage bias E_7' is set to operate about a value of conductance as illustrated at G, Fig. 3, larger values of E_7' produce a larger value of G, and smaller values of E_7' produce smaller values of G, in conformance with the voltage-conversion sensitivity characteristic of the devices. Without any compensation for variation of alternating current amplitudes, the loci n, n', Fig. 4, would be adversely modified by such changing amplitudes of input alternating current, and in inverse proportion to the constant circuit conductance, e. g., to the loci m, m', the vectors 9e and 12e being respectively increased to cp and cq, by increased alternating current amplitudes. The vectors originating at the point s are proportionately increased, and the voltage-output of the frequency-demodulator is then determined by the difference between sp and sq, for the same frequency-deviation, instead of by E_1-E_2 . In the devices of this invention, modification of the resultant conductance is effected in proportion to the square-root of the amplitudes of the impressed alternating currents. In these devices, the output-voltage for any particular frequency-deviation, and any particular alternating current amplitude, is governed by the product of two factors: the size of voltage A, and the rate of angular deviation of 9e from A in relation to frequency deviation. Each of these factors varies inversely with the resultant conductance; the output-voltage of the frequency-demodulators is thus governed by the inverse-square of the resultant conductance.

Having thus described several illustrative embodiments of my invention, it will be evident that

changes can be made in the form and arrangement of parts without departing from the spirit of my invention, as set forth in the appended claims, and I do not therefore limit the scope of the invention to such particular embodiments, or otherwise than by the terms of the appended claims.

What is claimed is:

1. A universal demodulator, for converting the envelope of frequency variations and the envelope of amplitude variations, of an impressed high-frequency carrier voltage having both amplitude-modulation and frequency-modulation, to the respective low-frequency alternating voltages corresponding to said envelopes, said demodulator having a double-diode, a first resistance connected between the cathodes of said double-diode, a resonant circuit having an inductance coil, a conductive connection between the anodes of said double-diode including inductance of said coil, a choke-coil connected in series with a second resistance from the half-resistance point upon said first resistance to the half-inductance point upon said included inductance between said anodes, capable of carrying the total unidirectional current of both diodes, a thermionic compensator-tube with anode, cathode, and control-grid, a source of unidirectional voltage connected to said compensator-anode through a second inductance coil and an anode-switch, coupling means coupling said resonant circuit and said choke-coil with voltages of said high-frequency, and coupling the resonant circuit with the anode-cathode of said compensator-tube, and circuit connections between said control-grid and said compensator-cathode, including a negative-voltage bias means and connections to said second resistance, impressing positive voltage from said second resistance upon said grid, and preventing application of said high-frequency upon said grid.

2. The combination with a demodulator for demodulating constant-amplitude frequency-modulated alternating currents, of a compensator device, said demodulator having a double-diode, a resistance connected between the cathodes of said double-diode, a resonant circuit having an inductance coil, a conductive connection between the anodes of said double-diode including inductance of said coil, and a choke-coil connected from the half-resistance point upon said resistance to the half-inductance point upon said included inductance between said anodes, capable of carrying the total unidirectional current of both diodes, said compensator device having a second resistance connected in series with said choke-coil, between the choke-coil and said half-resistance point, a thermionic compensator-tube having a cathode, anode, and control-grid, a source of unidirectional voltage connected to said compensator-anode through a second inductance coil, coupling means coupling said resonant circuit and said choke-coil with said frequency-modulated alternating currents, and coupling said resonant circuit with the anode-cathode of said compensator-tube, and circuit connections from said control-grid to said compensator-cathode, including a negative-voltage bias means and connections to said second resistance, impressing positive voltage from said second resistance upon said grid, and preventing application of voltage at the higher frequencies of said alternating currents upon said grid; whereby voltage is produced across said resistance, and determined by said frequency-modulation, independent of amplitude variations of said frequency-modulated alternating currents.

3. In a frequency-demodulator for producing output-voltages in direct proportion to the magnitude of frequency deviations above and below a centre frequency of input alternating currents, the means for producing an auxiliary unidirectional control-voltage, directly proportional to the amplitudes of said input alternating currents and independent of said frequency deviations, said demodulator having a double-diode, a first resistance connected between the cathodes of said double-diode, a resonant circuit having an inductance coil, a conductive connection between the anodes of said double-diode including inductance of said coil, a second inductance coil connected from the half-resistance point upon said first resistance to the half-inductance point upon said included inductance between said anodes, and coupling means coupling said resonant circuit and said second inductance coil with said input alternating currents, said producing means comprising a second resistance introduced in series with said second inductance coil, connected to said half-resistance point, and carrying the total unidirectional current of both diodes, and the determination of said total unidirectional current, by proportioning said inductances to yield a voltage-ratio greater than unity, for the ratio of alternating voltage across said second inductance to the alternating voltage across said included inductance between said anodes, and at said centre frequency, whereby said unidirectional control-voltage is produced across said second resistance.

4. In combination with the structure of claim 3, bridge-means including a third resistance connected to each terminal of said first resistance through a condenser, a connection from said second resistance to a junction at the half-resistance point upon said third resistance, and a ground-connection of negligible impedance to said junction, whereby voltages between the terminals of said first resistance produce no resultant voltages between said half-resistance points at the terminals of the second resistance, and whereby voltages across the terminals of the second resistance produce no resultant voltage across the terminals of the third resistance, and said junction is maintained at ground potential.

5. A universal demodulator, for converting the envelope of frequency variations and the envelope of amplitude variations, of an impressed high-frequency carrier voltage, to the respective output-voltages corresponding to said envelopes, said demodulator having a double-diode, a resonant circuit having an inductance coil, a conductive connection between the anodes of said double-diode including inductance of said coil, a first resistance connected between the cathodes of said double-diode, a choke-coil connected in series with a second resistance, having a terminal of said second resistance connected to the half-resistance point upon said first-resistance and a terminal of said choke-coil connected to the half-inductance point upon said included inductance between said anodes, and having the common terminal between said second resistance and choke-coil connected to ground by a negligible-impedance conductive connection, said choke-coil and second resistance being capable of carrying the total unidirectional current of both diodes, a thermionic compensator-tube with anode, cathode, and control-grid, a source of unidirectional voltage with positive terminal connected to said compensator-anode through a second inductance coil and an anode-switch, and with negative ter-

minal connected to ground, coupling means coupling said resonant circuit and said choke-coil with voltages of said high-frequency and coupling the resonant circuit with the anode-cathode of said compensator-tube, circuit connections between said control-grid and said compensator-cathode, including a negative-voltage bias means and connections to said second resistance, impressing positive voltage from said second resistance upon said grid, and preventing application of voltage of said high-frequency across the grid-cathode of the compensator-tube, and bridge-means, including a third resistance having each terminal thereof connected to a terminal of said first resistance through a condenser, a ground connection at the half-resistance point upon said third resistance, and a fourth resistance with one terminal grounded, and the other terminal connected to the half-resistance point upon said first resistance through a condenser.

6. The combination, with the structure of claim 5, of means for selectively amplifying the output voltages across said third resistance, or across said fourth resistance, including a resistance-coupled thermionic push-pull amplifier having cathodes connected to ground, and a two-position switching means, one position coupling a first control-grid of said amplifier and, a second control-grid of said amplifier to the terminals of said third resistance, and closing said anode-switch; the other position connecting said first control-grid to the terminal of said fourth resistance opposite said ground connection, connecting said second control-grid to an output-resistance of said amplifier for phase inversion, and opening said anode-switch.

7. The combination with a frequency-demodulator, of a bridge circuit, said frequency-demodulator having a double-diode, a first resistance connected between the cathodes of said double-diode, a resonant circuit having an inductance coil, a conductive connection between the anodes of said double-diode including inductance of said coil, a choke-coil connected from the half-resistance point upon said first resistance to the half-inductance point upon said included inductance between said anodes, and coupling means coupling said resonant circuit and said choke-coil with modulated alternating voltages, said bridge circuit including a second resistance connected in series with said choke-coil, and having one terminal connected to the half-resistance point upon said first resistance, and the common junction of the other terminal and choke-coil connected to ground, a third resistance connected to each terminal of said first resistance through a condenser, and having the half-resistance point of said third resistance connected to said common junction, and a fourth resistance with one terminal connected to ground and the other terminal connected through a condenser to said half-resistance point upon said first resistance.

8. The combination with the structure of claim 7, of a thermionic compensator-tube having an anode, a cathode and a control-grid, a source of unidirectional voltage with positive terminal connected to said compensator-anode, and negative terminal connected to ground, and to the compensator-cathode through a bias resistance, and connections between said compensator control-grid and compensator-cathode including connections to said second resistance, said coupling means including means coupling the anode-cathode of said compensator-tube with said resonant circuit.

9. A universal demodulator for simultaneous demodulating frequency-modulation and amplitude-modulation from a high-frequency carrier-voltage impressed upon the demodulator, 5 said demodulator having a double-diode, a resonant circuit, balanced-bridge connections to said double-diode including a first resistance connected across the cathodes of said double-diode, a second resistance connected across said first resistance through a condenser connected to each terminal of said second resistance, and having the half-resistance point thereon connected to ground, a third resistance connected from the half-resistance point upon said first resistance to the half-resistance point upon said second resistance, and a fourth resistance connected to ground and through a condenser to the half-resistance point upon said first resistance, and thermionic-tube means having a control-grid 10 modifying the conductance of said resonant circuit, including connections from said third resistance to said control-grid.

10. The combination with a frequency-demodulator having a resonant circuit comprising an inductance coil shunted by a condenser, a choke-coil, a voltage-rectifying means including a first diode means in series with a resistance, a second voltage-rectifying means including a second diode means in series with a second resistance, and 15 circuit connections including each diode-anode of said diode means conductively connected to a separate terminal upon said inductance coil, a common junction between said rectifying means, and the conductive connection of said common junction to an intermediate terminal upon said inductance coil between said separate terminals, through said choke coil, of a control resistance connected in series with said choke-coil, carrying the total thermionic currents of both said 20 first and second diode means, whereby unidirectional control-voltage is produced thereon, with magnitudes independent of frequency-modulation, and proportional to the amplitudes of alternating currents impressed upon said resonant circuit.

11. A frequency-demodulator for converting frequency-modulated alternating currents into amplitude-modulated voltages, said demodulator having resonant circuit means including inductance coil means, a double-diode voltage-rectifying means connected with said inductance coil means, including a first diode-anode, a second diode-anode, diode-cathode means for said diode-anodes, a conductive connection from each of said diode-anodes to a separate terminal upon said inductance coil means, and conductive circuit connections from said diode-cathode means to an intermediate terminal upon said inductance coil means between said separate terminals, including a circuit through a control-resistance carrying the total thermionic currents of both said diode-anodes; a thermionic tube having a cathode, anode, and grid, and means for controlling alternating currents in said resonant circuit means including a coupling between said anode and said resonant circuit means, and connections between said grid and said control-resistance for modifying said alternating currents, to provide a constant ratio of conversion of frequency-deviations into output-voltages, independent of amplitude variations of said alternating currents.

12. The combination with a frequency-demodulator for providing amplitude-modulated output-voltages from impressed frequency-modu-

lated currents, of compensating means for compensating undesired variations of said output-voltages due to impressed amplitude variations, said demodulator having resonant circuit means for determining voltages responsive to amplitudes and frequencies of carrier currents, and voltage-rectifying means connected with said resonant circuit means for deriving unidirectional voltages therefrom responsive to the envelope of said carrier current amplitudes, including diode means serially connected with resistance means, said compensating means including a control means for controlling alternating currents in

5 said resonant circuit means, having a thermionic tube with a cathode, anode, and grid, a coupling means coupling said anode with said resonant circuit means for modifying alternating currents therein, and conductive circuit connections between said grid and said cathode including circuit connections with said resistance means synchronously applying said envelope-responsive voltages, to provide a constant ratio of conversion of frequency-deviations into output-voltages, independent of variations of amplitude of 10 said impressed carrier currents.

EDWARD H. LANGE.
